CLAIM

The ornamental design for a tool for a press brake, as shown and described.

DESCRIPTION

FIG. 1 is a top front perspective view of the tool for a press brake in a closed condition;

FIG. 2 is a top rear perspective view of the tool for a press brake in a closed condition;

FIG. 3 is a bottom front perspective view of the tool for a press brake in a closed condition;

FIG. 4 is a bottom rear perspective view of the tool for a press brake in a closed condition;

FIG. 5 is a front elevational view of the tool for a press brake in a closed condition;

FIG. 6 is a rear elevational view of the tool for a press brake in a closed condition;

FIG. 7 is a left side elevational view of the tool for a press brake in a closed condition;

FIG. 8 is a right side elevational view of the tool for a press brake in a closed condition;

FIG. 9 is a top plan view of the tool for a press brake in a closed condition;

FIG. 10 is a bottom plan view of the tool for a press brake in a closed condition;

FIG. 11 is a top front perspective view of the tool for a press brake in an open condition;

FIG. 12 is a top rear perspective view of the tool for a press brake in an open condition;

FIG. 13 is a bottom front perspective view of the tool for a press brake in an open condition;

FIG. 14 is a bottom rear perspective view of the tool for a press brake in an open condition;

FIG. 15 is a front elevational view of the tool for a press brake in an open condition;

FIG. 16 is a rear elevational view of the tool for a press brake in an open condition;

FIG. 17 is a left side elevational view of the tool for a press brake in an open condition;

FIG. 18 is a right side elevational view of the tool for a press brake in an open condition;

(Continued)

FIG. 19 is a top plan view of the tool for a press brake in an open condition;
 FIG. 20 is a bottom plan view of the tool for a press brake in an open condition;
 FIG. 21 is a top front exploded perspective view of the tool for a press brake;
 FIG. 22 is a top rear exploded perspective view of the tool for a press brake;
 FIG. 23 is a bottom front exploded perspective view of the tool for a press brake;
 FIG. 24 is a bottom rear exploded perspective view of the tool for a press brake;
 FIG. 25 is a front elevational view of an upper component of the tool for a press brake shown separate for clarity of disclosure;
 FIG. 26 is a rear elevational view thereof;
 FIG. 27 is a left side elevational view thereof;
 FIG. 28 is a right side elevational view thereof;
 FIG. 29 is a top plan view thereof;
 FIG. 30 is a bottom plan view thereof;
 FIG. 31 is a front elevational view of a center component of the tool for a press brake shown separate for clarity of disclosure;
 FIG. 32 is a rear elevational view thereof;
 FIG. 33 is a left side elevational view thereof;
 FIG. 34 is a right side elevational view thereof;
 FIG. 35 is a top plan view thereof;
 FIG. 36 is a bottom plan view thereof;
 FIG. 37 is a front elevational view of a lower component of the tool for a press brake shown separate for clarity of disclosure;
 FIG. 38 is a rear elevational view thereof;
 FIG. 39 is a left side elevational view thereof;
 FIG. 40 is a right side elevational view thereof;
 FIG. 41 is a top plan view thereof; and,
 FIG. 42 is a bottom plan view thereof.
